ATTORNEY.

UNITED STATES PATENT OFFICE

103,367

DESIGN FOR A DISPLAY CONTAINER FOR FRUIT OR SIMILAR ARTICLE

Morris Cooper, Chicago, Ill.

Application February 27, 1936, Serial No. 61,387

Term of patent 7 years

To all whom it may concern:

Be it known that I, Morris Cooper, a citizen of the United States, residing at Chicago, in the county of Cook and State of Illinois, have invented a new, original, and ornamental Design for a Display Container for Fruit, or Similar Article, of which the following is a specification, reference being had to the accompanying drawing, forming part thereof.

In the drawing,

Figure 2 is a top plan view of a display container for fruit, or similar article showing my new design.

I claim:

The ornamental design for a display container for fruit, or similar article as shown.

MORRIS COOPER.
